UNITED STATES PATENT OFFICE.

JOHN F. MEYER, OF CHICAGO, ILLINOIS.

VENDING MACHINE.

Application filed February 14, 1925. Serial No. 9,077.

The principal object of my invention is to provide a vending machine embodying devices which will effectually prevent improper and fraudulent operation thereof and which will insure that operation can only be performed after insertion of a proper coin.

A further object is to provide a vending machine of improved construction, which may be inexpensively made, but which shall nevertheless have the necessary strength.

Another object of my invention is to provide a vending machine for cards or other thin articles which shall be efficient in operation, which shall insure the proper feeding of the desired number of cards, and which may be conveniently adjusted to vary the number of cards to be vended and to permit use with different thicknesses of cards.

In the accompanying drawings in which I have shown a selected embodiment of my invention:

Fig. 1 is a vertical sectional view through a machine embodying my invention.

Fig. 2 is a fragmentary section similar to Fig. 1, but showing the parts in a different position.

Fig. 3 is a fragmentary view similar to Fig. 1, but showing the parts as affected by a proper coin.

Fig. 4 is a view similar to Fig. 2, but showing the parts after they have been moved to operative position as permitted by use of a proper coin.

Fig. 5 is a section taken on the line 5—5 of Fig. 1.

Fig. 6 is a bottom plan view of my invention.

Fig. 7 is a section on the line 7—7 of Fig. 5.

Fig. 8 is a section on the line 8—8 of Fig. 5.

Fig. 9 is a section on the line 9—9 of Fig. 5.

Referring now to the drawings I have shown my invention as embodied in a machine for the vending of cards although it is obviously capable of use in other connections. Such a machine comprises a cabinet 1 containing a compartment having therein a plurality of cards 2 supported by a plate 3 and having a weight 4 resting on the top of the stack of cards to hold them

against the plate 3. This plate is cut away near its rear portion, as shown at 5 (Fig. 5) to permit operation of the mechanism for pulling out the cards. A portion of this plate has been broken away in Fig. 5 for better illustration of the mechanism. Immediately in front of the plate 3 is a table 6 onto which a card is pulled upon operation of the machine.

The table 6 has an opening therein, in which opening is disposed my vending mechanism, said mechanism and the table being supported upon the base 7, which is detachably secured to the cabinet as by a screw 8 and bolt 8'; so that the base, vending mechanism, and table may be handled as a unit.

Resting on the base 7 is the base plate 9 upon which the outer end of the delivery slide 10 rests. The base plate is secured to the base and the delivery slide is held against the base plate by means of a pair of clamp plates 11, whereby the delivery slide may reciprocate in respect to the base plate. Suitable fastening means 12 pass through the clamp plates and base plate, as plainly shown in Figs. 5 and 7.

Mounted upon the base 7 immediately in the rear of the base plate 9 is the base bar 13, best shown in Fig. 6. This bar has a rounded front end 14 received within a corresponding recess in the rear of the base plate. The base bar is secured to the base as by screws 15 at the rear end thereof and by engagement of the delivery slide at the front end, the delivery slide in turn being retained by the clamp plates 11. The delivery slide comprises a handle 16 at its forwarded end for operation and is further provided with a substantially circular opening 17, which may be made of any desired size depending upon the character of coin which it is intended that the machine be operated by, said opening being of a size to receive the coin. Extending from the rear side of the opening 17 is an elongated slot 18, best shown in Figs. 2 and 6. Extending across the slot 18 are a plurality of locking bars 19 and 20. In this embodiment I have selected two of these bars as illustrative, but it is obvious that this number may be varied as desired.

Mounted on the rear end of the delivery slide 10 is vending means exemplified by the

card puller 21. This puller is preferably made of thin sheet material bent to the form shown and having its rear edge turned over as at 22 to form a shoulder to engage the rear edge of the bottom card of the stack, the puller springing up sufficiently to engage that card. It is desirable to make the puller of sheet material of substantially the thickness of one of the cards to be vended, so that when its edge is turned over as at 22, the shoulder will be just the proper thickness. In making the puller of this thickness of material, it has been found that it is not sufficiently rigid to continue to do satisfactory work and I have therefore provided the reinforcement 23 extending substantially throughout the length of the puller and made of sufficiently heavy material to furnish adequate support for the thin sheet metal thereof.

Depending from the rear of the delivery slide 10 is a stop member which may comprise a screw 24 and which reciprocates in a slot 25 in the base bar 13. By reference to Fig. 6, it will be seen that this construction will serve to hold the parts together and at the same time the screw 24 will act as a stop because of its engagement with the ends of the slot 25. The puller is secured to the delivery slide by screws 26 passing through the puller, the reinforcement 23 and entering the delivery slide 10. The parts are made of thin material and it is well known that it is difficult to obtain sufficient holding power with the end threads of a screw of this type. I have therefore provided slots 27 in the base bar 13 so as to receive the ends of these screws and permit the use of longer screws, thereby insuring better holding power between the screws and the base bar.

The base bar 13 is provided with projecting lugs 28 provided with apertures in which are received corresponding lugs 29 on a keeper plate 30 disposed on top of the delivery slide. By upsetting the ends of the lugs 29, the keeper plate is rigidly and permanently secured to the base bar and the delivery slide is reciprocably mounted between the base bar and the keeper plate. Loosely mounted upon the rivet 31, which is secured to the keeper plate, is the trigger 32 having a cam projection 33 on the under side thereof and provided at its end with a downwardly extending hook 34. The cam projection and the hook extend downwardly through an opening 35 in the keeper plate and are held against downward movement by contact therewith. On either side of the trigger are lugs 36 struck up from the keeper plate, and co-operating with a spring 37 upon the upper surface of the keeper plate to maintain the trigger in position. The spring in turn is held in position by a lug 38, which together with the

lug 36 effectively prevents its being swung to a position out of engagement with the trigger.

Referring particularly to Fig. 7, it will be seen that the opening 17 is provided with walls 39 inclined downwardly and outwardly from the center of the opening so that there is little danger of a coin or any other substance becoming wedged therein. The advantage of this feature will be explained later.

In operation, a coin of the proper size is placed within the opening 17 in the delivery slide, which is shown in its normal position in Fig. 1. This slide without the coin can be moved rearwardly only to the position shown in Fig. 2, in which position the locking bar 20 will be engaged by the hook 34 of the trigger. It will therefore be seen that it is impossible for the puller 21 to engage the rear edge of a card to vend the same. However, when the proper coin is placed in the opening 17 and the delivery slide is pushed rearwardly, the coin which is indicated at 40 in Fig. 3, will engage the cam projection of the trigger thereby lifting the hook out of position wherein it would engage the locking bar 20. From an inspection of Fig. 3, it will be seen that this action takes place before the delivery slide is moved sufficiently for the locking bar to engage the hook 34. The rearward movement of the delivery slide then continues to the position shown in Fig. 4, at which time the coin which is being carried rearwardly in the opening 17, comes over the enlarged end 41 of the opening 42 in the base bar 13. The coin is then discharged to the coin receptacle, as indicated in dotted lines in Fig. 4. The forward movement of the delivery slide causes a card to be vended because of engagement of the shoulder 22 with the rear edge of the lowermost card of the stack. During this movement the cam projection 33 will ride over the locking bars 19 and 20, the parts returning to the position shown in Fig. 1.

If a smaller coin than the proper one is used, it will be discharged through the small end 43 of the opening 42 in the base bar 13, before it has had an opportunity to lift the trigger. Although it may have lifted the trigger sufficiently to cause the hook 34 to pass the locking bar 20, the coin will be discharged before the hook has had a chance to pass the locking bar 19, and therefore the rearward movement of the delivery slide will be arrested. Moreover, if a washer or a slug be used having a hole in the middle thereof, the cam projection will enter that hole and permit the trigger to drop so that the hook 34 will catch the bar 19 even though it may have missed the bar 20. It will therefore be obvious that the use of washers, small coins or other im-

proper devices for defrauding the machine, is rendered impossible.

It is a somewhat prevalent practice to attempt to defraud a machine of this character by the use of paper or cardboard or possibly a coin wedged into the opening 17 so that it will not be ejected therefrom and therefore the machine can be operated continuously on one coin or piece of cardboard 10 or the like, until the machine is exhausted. To avoid such fraud I have made the walls of the opening 17 in the form described so that it will be extremely difficult to wedge a coin or piece of paper therein, such an 15 article naturally falling out of the opening because of the outwardly inclined wall thereof. Furthermore, it will be apparent that the trigger is lifted by the coin against the tension of the spring 37, so that when 20 the coin comes to a position over the enlarged end 41 of the opening 42, it will be positively ejected by the action of the spring transmitted to the trigger. In actual practice I find that this action is a 25 very positive and sure one.

Another means of defrauding a machine of this type is to insert a proper coin, or any other article, which will actuate the trigger, pull the delivery slide out until a card is partially projected from the cabinet and then pull the card the rest of the way with the fingers and return for another without bringing the delivery slide to its outward limit. This type of fraud is effectually prevented by the provision of the second locking bar 19, which is so placed that when a card has been pulled out a sufficient distance 30 to grasp with the fingers, or with an instrument of any kind, the trigger will drop to 40 bring the hook into engagement with the bar 19 so that the delivery slide may not be again moved rearwardly.

Another means which has been practiced to defraud this machine is to operate the delivery slide so violently that the trigger will jump out of position and the hook will rest on top of the keeper plate 30. This type of fraud is effectually prevented by the arrangement of lugs shown, these lugs not only retaining the trigger in its place, but 50 also effectually maintaining the spring in contact with the trigger.

By attaching the trigger loosely to the keeper plate by means of the vertical rivet, I provide a structure which is extremely easy and inexpensively made and which will permit a vertical pivotal movement of the trigger just as effectually as if a horizontal piv-

ot were provided, it being obvious that the provision of such a pivot would be greatly 60 more expensive.

In the past it has been customary to provide various devices for ejecting comparatively large articles such as boxes of matches and packages of gum by pushing 65 the bottom one of a stack of such articles out from its position at the bottom of the stack. In vending comparatively thin articles such as cards, however, a different problem is involved because of the difference in 70 the thickness. I, therefore, prefer to provide a pulling mechanism which, as exemplified herein, comprises the puller 21, which is normally beneath the stack and which may be released by a suitable coin so as to 75 travel backwardly to the extreme rear of the stack and there engage the rear edge of the bottom card. The thickness of cards varies considerably and moreover at times it may be desired to vend more than one card with 80 one movement of the puller and therefore it becomes necessary to provide means for this purpose. Such means is exemplified in this application by the slideable gauge in the form of a plate 44 having slots 45 to receive 85 screws 46 in the front wall of the card compartment. By this means the plate may be adjusted vertically to insure that only one card or any other desired number shall be vended at one operation, through the delivery slot 47. While I have referred to cards, it is understood by that term that I intend to cover all articles of similar characteristics.

I am aware that changes in the form, construction and arrangement of parts may be made without departing from the spirit and without sacrificing the advantages of the invention and I reserve the right to make all such changes as fairly fall within the scope 100 of the following claim.

I claim:

In a coin controlled delivery mechanism, the combination of a base, a delivery slide on the base, a keeper on the base forming a 105 guide for the slide, a locking bar on the slide, a trigger on the keeper, and means on the keeper for holding said trigger in co-operative relation with the locking bar and comprising lugs on opposite sides of the 110 trigger, another lug, and a spring mounted on the keeper and retained in position engaging the top of the trigger by one of said trigger lugs and said other lug.

JOHN F. MEYER.
